(57) **CLAIM**

The ornamental design for an intraoral scanning device, as shown and described.

DESCRIPTION

FIG. 1 is a top perspective view showing a new design for an intraoral scanning device;

FIG. 2 is a bottom perspective view of the intraoral scanning device of FIG. 1;

FIG. 3 is a top view of the intraoral scanning device of FIG. 1;

FIG. 4 is a bottom view of the intraoral scanning device of FIG. 1;

FIG. 5 is a front view of the intraoral scanning device of FIG. 1;

FIG. 6 is a rear view of the intraoral scanning device of FIG. 1;

FIG. 7 is a left-side view of the intraoral scanning device of FIG. 1; and,

FIG. 8 is a right-side view of the intraoral scanning device of FIG. 1.

The broken lines are included for the purpose of illustrating portions of the intraoral scanning device that form no part of the claimed design.
